UNITED STATES PATENT OFFICE.

PATRICK J. HAND, OF ROCKHAM, SOUTH DAKOTA.

MONOPOD.

1,175,352.

Specification of Letters Patent. Patented Mar. 14, 1916.

Application filed October 1, 1915. Serial No. 53,607.

To all whom it may concern:

Be it known that I, PATRICK J. HAND, a citizen of the United States, residing at Rockham, in the county of Faulk and State 5 of South Dakota, have invented a new and useful Monopod, of which the following is a specification.

The device forming the subject matter of this application is adapted to be employed 10 for supporting cameras and other articles, and one object of the invention is to provide novel means whereby the camera may be shifted readily to assume different positions with respect to the horizontal and the 15 vertical.

Another object of the invention is to provide in a device of this type, a supporting structure which at the will of an operator 20 may be employed as a Jacob's staff, as a tripod, or as a combination of the structures above mentioned.

It is within the province of the disclosure 25 to improve generally and to enhance the utility of devices of that type to which the present invention appertains.

With the above and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed, without deviating from the spirit of the invention.

In the accompanying drawings:—Figure 1 shows the invention in side elevation; Fig. 2 is a cross section taken on the line 2—2 of Fig. 1; Fig. 3 is a cross section taken on the 40 line 3—3 of Fig. 1; Fig. 4 is a perspective showing a portion of the platform; Fig. 5 is a perspective delineating the upper end of the upright; Fig. 6 is a fragmental section showing the ground engaging prong in reversed position; Fig. 7 is a side elevation of the attaching screw; Fig. 8 is a section detail illustrating the co-operation between the parts shown in Figs. 7, 5 and 4. Fig. 9 is a sectional detail illustrating a modified 45 means for holding the ground engaging prong in place.

In carrying out the present invention there is provided a longitudinally extensible standard embodying an outer tube 1, an intermediate tube 2, an inner tube 3 and an 50 upright 4, relative longitudinal movement

between the parts above mentioned being prevented by means of set screws 5. The upper end of the upright 4 terminates in a downwardly inclined, flattened head 6 united 60 with the upright by means of a curved extension 7. In the head 6 there is formed a slot 8 which is prolonged downwardly into the curved extension 7. Intermediate its ends, the slot is enlarged to form an 65 opening 9.

The numeral 10 indicates a platform which may constitute a part of a camera 11. In the platform 10 there is formed an opening 12, a portion of the material freed in 70 the fashioning of the opening, being bent downwardly to form side ears 14 adapted to engage opposed edges of the head 6. The invention comprises a screw 15 having an enlarged shoulder 16, a finger piece 17 being 75 united with the screw by means of a pivot element 18. The ears 14 engage the opposite edges of the head 6, the screw 15 is threaded as shown at 19 into the camera or other object 11, and thus the camera and the 80 platform 10 are bound firmly on the head 6. By loosening the screw 15, the camera and the platform may be slid along the head 6. The screw 15 may lie in that portion of the slot 8 which is disposed in the extension 7, and under such circumstances, the 85 camera 11 will point upwardly, in a vertical direction. By causing the platform 10 and the camera 11 to traverse the curved extension 7 and the head 6, the position of 90 the camera with respect to the vertical may be adjusted through a wide range. When it is desired to remove the camera, the screw 15 is slid along until the shoulder 16 lies adjacent the opening 9, through which the 95 shoulder is adapted to pass, the flattened head 17 being removed through the slot 8. It is therefore unnecessary to detach the screw from the camera and the platform, when it is desired to separate these elements 100 from the head 6. The camera 11 may be raised and lowered by loosening the set screws 5, thus permitting an extension or a contraction of the longitudinally extensible standard embodying the parts 1, 2, 3 and 4. 105

The invention comprises a tubular cap 20, internally threaded at its ends as shown at 21 and 22. Across the cap 20 extends a partition 23 from which projects an earth engaging prong 24. When the end 22 of the 110 cap 20 is threaded onto the lower end of the outer tube 1, the prong 24 is in the de-

pending, earth engaging position shown in Fig. 1, but when it is unnecessary to use the prong, the prong may be reversed and be disposed within the contour of the tube 1, as shown in Fig. 1, under which circumstances, the threaded end 21 of the cap 20 will be engaged with the tube. Pivoted as shown at 25 to the cap 20 is an outstanding arm 26, the lower end 27 of which bears against the side of the cap. Since the arm 26 is pivotally mounted, it may be folded up against the side of the cap, and be disposed in an out-of-the-way position if desired. The arm 26 exercises two functions. First, it is adapted to receive the foot of an operator, to facilitate the thrusting of the prong 24 in the ground: secondly, it acts as a lever whereby the cap 20 may be threaded onto the end of the tube 1 and be removed therefrom.

Surrounding the outer tube 1 near to its upper end is an upper collar 28, a lower collar 29 surrounding the tube adjacent the lower end of the tube. These collars are duplicates and but one of them need be described in detail. The lower collar 29 is flexed outwardly at its ends to form ears 30 united by a clamp screw 31. The clamp screw 31 may be tightened up to cause the collar 29 to engage the tube 1. Secured to the collar 29 is a side plate 32 having outstanding ears 33 carrying pivot elements 34. On the pivot elements 34 and on the clamp screw 31 are mounted to swing legs 36 having slots 37. Assembled with the several ears of the upper collar 28 pivotally, as described in connection with the lower collar, are braces 35 carrying wing bolts 38 mounted to move in the slots 37 of the legs 36 and 40 adapted to be clamped in adjusted positions therein.

The collars 28 and 29 may be slipped off the tube 1, together with the legs 36 and the braces 35, the device under such circumstances being supported on the prong 24 only. If desired, the legs may be used in combination with the prong, as shown in Fig. 1. Further, the legs 36 may be used alone, under which circumstances, the prong 24 is inverted as shown in Fig. 6. Any one of the legs 35 may be raised and lowered independently of the other legs, thus permitting a ready adjustment when the structure is used upon a sloping hillside.

It will be observed that the partition 23 in the cap is provided with oppositely projecting lugs 50, either of which fits closely within the member 1 to aid in holding the cap firmly in place.

The device forming the subject matter of this application preferably is made of metal and it may be made in various sizes to meet the demands of the trade.

The platform 10 may be provided with threaded holes 100 which will be of use

when a securing means differing from, or in addition to the screw shown in Fig. 7, is required.

In Fig. 9 of the drawings, the ground-engaging prong is denoted by the reference character 101 and is carried by a reducer 102 threaded exteriorly at its smaller end as shown at 103 and threaded interiorly at its larger end as shown at 104. When this form of the invention is used, the standard 75 is threaded both exteriorly and interiorly as will be understood readily. In general, any suitable means may be provided for mounting the prong in place.

The tube 3 may be telescoped into the tube 2 and the tube 2 may be telescoped into the tube 1, the upright 4 being telescoped into the tube 3. Legs 36 may be swung upwardly, the cap 20 being turned end for end. The entire structure may then be inverted 85 and may be carried about by means of the arm 26, the latter serving as a handle.

Having thus described the invention, what is claimed is:—

1. In a device of the class described, a standard provided at its upper end with a lateral head having a slot extended vertically into the standard; a platform supported on the head; and a clamping device assembled with the platform and movable 95 in the slot, the clamping device engaging the under surface of the head to one side of the slot.

2. In a device of the class described, a standard embodying a lateral head having 100 a slot extended vertically into the standard; the slot including an enlargement; a platform supported on the head; a securing member coacting with the platform and movable in the slot, the securing member including an enlarged shoulder engaging the head on both sides of the slot and adapted to pass through the enlargement, the securing member including a flattened head adapted to pass through the slot.

3. In a device of the class described, a tubular standard; a cap into either end of which the end of the standard may be inserted, the cap embodying a partition constituting an abutment for the standard; and a prong projecting from the partition, the cap being reversible to dispose the prong within the standard and in projecting relation with respect to the standard.

4. In a device of the class described, a tubular standard; a cap, either end of which may be assembled with the standard; and a ground-engaging prong projecting from the cap intermediate the ends of the cap.

5. In a device of the class described, a tubular standard; a cap assembled with the lower end of the standard; a prong projecting from the cap, the cap being reversible on the standard to dispose the prong within and without the standard; a pair of 130

- collars removably mounted on the standard; legs pivoted to one collar; braces pivoted to the other collar; and means for adjustably assembling the braces with the legs.
- 5 6. In a device of the class described, a standard; a cap threaded onto the standard; a prong projecting from the cap; and an arm extended laterally from the cap, the arm constituting means for rotating the cap

and a foot rest for seating the prong in the 10 earth.

In testimony that I claim the foregoing as my own, I have hereto affixed my signature in the presence of two witnesses.

PATRICK J. HAND.
